UNITED STATES PATENT OFFICE.

FRANK J. YOUNGER, OF WALLACE, CALIFORNIA, ASSIGNOR OF TWENTY-SIX ONE-HUNDREDTHS TO MORITZ HEINRICH ROEBER AND FIFTEEN ONE-HUNDREDTHS TO JOE CALCATERRA, BOTH OF WALLACE, CALIFORNIA.

DESIGN FOR A STANDARD OR BASE FOR DISPENSING APPARATUS.

Application filed November 23, 1921. Serial No. 517,360. Term of patent 14 years.

To all whom it may concern:

Be it known that I, FRANK J. YOUNGER, a former subject of the Emperor of Germany, who has declared his intention of becoming a citizen of the United States, and who has taken out his first papers, and a resident of Wallace, in the county of Calaveras and State of California, have invented a new, original, and ornamental Design for a Standard or Base for Dispensing Apparatus, of which the following is a specification, reference being had to the accompanying drawing, forming a part thereof.

I claim:

The ornamental design for a standard or base for dispensing apparatus substantially as shown.

FRANK J. YOUNGER.
